Dec. 194

Job E. Owens, Jacob Ebert & Elbridge G. Dyer
of Hamilton, Ohio.

Letters Patent No. 294. Dated June 25, 1850

the Schedule referred to in these Letters Patent and making
part of the same.

To all whom it may concern:

Be it known that we, Job E. Owens, Jacob Ebert and Elbridge G. Dyer of Hamilton in the County of Butler and State of Ohio, have invented or produced a new and ornamental Design for Stoves and we do hereby declare the following to be a full, clear and exact description of the same, reference being had to the annexed drawings making part of this specification, in which Fig. 1. represents the lower front plate, having a large rectangular panel a, ornamented at its centre with a symmetrical ornament, one fourth of which is represented at b.

Fig. 2. is one of the oven doors, and contains at its centre a symmetrical ornament, one forth of which is shown at c.

Fig 3 is one of the legs decorated by arabesque and scroll d as shown.

Fig 4 is one of the side plates with lower oven door d' in situ.

Fig 5 is the back plate and contains two middle and

Des. 294

two side panels c. f. g. g. The upper middle panel contains a symmetrical ornament, the half of which is represented. The configuration of the various moldings is indicated at j on the several figures. The door is decorated at its centre with the same ornament as that upon the lower front plate.

Having thus fully and exactly described the ornaments of our stove, what we claim therein as new, and desire to secure by Letter Patent, is the combined ornamental design and configuration of plates for a cooking-stove substantially as herein set forth and represented in the accompanying drawings.

In testimony whereof, we have hereunto set our hands before two subscribing witnesses.
